C. H. LUTHMAN.
RAILWAY TONGS.
APPLICATION FILED NOV. 8, 1916.

Patented June 26, 1917.

1,231,035.

UNITED STATES PATENT OFFICE.

CHARLES H. LUTHMAN, OF HAMMOND, INDIANA, ASSIGNOR TO CLARENCE C. ZIMMERMAN, OF PARK RIDGE, ILLINOIS.

RAILWAY-TONGS.

1,231,035.

Specification of Letters Patent. Patented June 26, 1917.

Application filed November 8, 1916. Serial No. 130,133.

To all whom it may concern:

Be it known that I, CHARLES H. LUTHMAN, a citizen of the United States, residing at Hammond, in the county of Lake and 5 State of Indiana, have invented certain new and useful Improvements in Railway-Tongs, of which the following is a specification.

This invention relates to that class of implements extensively used on railways for 10 the handling of ties and rails. Until recently it has been the custom to provide, for the handling of ties, two kinds of tongs, one adapted to be manipulated by only one workman, and commonly known as pulling 15 or placing tongs, and the other adapted to be manipulated by two workmen, and commonly known as carrying tongs. For the purpose of handling and placing rails, a third construction of tongs has been employed, this latter being adapted to be 20 handled by two workmen, one on each side of the rail.

In an application heretofore filed by me on the first day of April 1915, Serial No. 25 18,526, I have disclosed and claimed a construction of tie tongs adapted to combine the functions of the pulling or placing tongs and the carrying tongs; the jaws of the tongs being provided with two sets of tie-engaging teeth, one set engaging the tie with the handle levers in approximately upright position so as to be grasped by the two hands of a single operative, and the other set engaging the tie with the handle levers 30 inverted and extending in an approximately horizontal position and adapted to be grasped by the hands of two operatives, one on each side of the tie.

The principal object of my present invention is to dispense with the necessity of 40 providing both tie tongs and rail tongs as separate implements, so as to thereby reduce the number of implements required to be kept on hand on any section of a railway 45 track, and this object I accomplish through the provision of an auxiliary pair of rail gripping or clamping members on the tie tongs, thus adapting the latter for the handling of both ties and rails.

50 In the most complete and preferred embodiment of my present invention, the tongs are provided with two sets of tie-engaging teeth, one for pulling or placing, and the other for carrying, as above described, and 55 also with a pair of rail grips or clamps, whereby a single pair of tongs is adapted

to the handling of ties in both of the ways mentioned, and also to the carrying of rails. It should be understood, however, that so far as the rail-carrying feature is concerned, 60 this may be embodied in or applied to other forms and constructions of tie tongs than that specifically above mentioned.

In the accompanying drawing I have 65 illustrated my invention in its most complete and preferred mechanical form, and referring thereto,—

Figure 1 is a side elevation of the tongs; Fig. 2 is an elevational view showing the tongs in tie-pulling or placing position; 70

Fig. 3 is a perspective elevation showing the tongs in rail-carrying position; and Fig. 4 is a side elevation showing the tongs reversed and in tie-carrying position.

Referring to the drawing, 5 designates 75 each of a pair of duplicate or similarly shaped members pivotally connected intermediate their ends by a pivot pin or bolt 6. The handle arms of the levers, formed by pivotally connecting the members together, 80 are straight and are equipped at their outer ends with outwardly turned hand grips 7 by means of which the tongs are operated and carried. The shorter arms or jaws of the levers are outwardly offset relatively to 85 the handle arms, preferably being shaped substantially as shown in Figs. 2, 3 and 4, and the lower ends of the jaws are provided with opposed inwardly projecting tie-engaging devices or teeth 8 adapted to grasp 90 and hold between them a tie 9. When the teeth 8 are engaged with a tie, as shown in Fig. 2, the long arms or handles of the tool are sufficiently close together to enable the hand grips 7 to be readily seized, and the 95 tongs operated, by a single workman; the tongs when thus engaging a tie being used for pulling it out of or pushing it into its final position, and having the function of what is known as pulling or placing tongs. 100

In order to adapt the tongs for carrying purposes each of the members 5 is equipped intermediate and preferably approximately midway between the pivot 6 and the teeth 8 with a tooth or tie-engaging device 11 105 which projects in a direction opposite to the projection of the teeth 8. When it is desired to employ tongs for lifting and carrying purposes the members 5 are swung on their pivot 6 into the reversed position 110 shown in Fig. 4, so as to bring the teeth 11 into co-operative relation with a tie 9, the

teeth being then adapted to grasp a tie between them when the outer ends of the handles are lifted. It will be noted that in this position of the tongs the handles are 5 disposed substantially horizontally and project a considerable distance beyond the sides of the tie, so that the workmen lifting and carrying the tie by means of the handles will have ample room to walk on each side of 10 the tie. Furthermore, the handles in this position are disposed quite low relatively to the tie so that when the workmen stand erect the tie will be lifted clear of the ground.

15 In order to adapt the same tongs for rail-carrying purposes each of the members 5 is further equipped with an inwardly projecting rail-grip or clamp 12 secured to the lever closely adjacent to and slightly below 20 the pivot 6. When the handles are swung downwardly to the approximately horizontal position illustrated in Fig. 3 (but without reversing the tongs as in Fig. 4) the grips 12 are adapted to engage the web of 25 a rail 13 directly beneath the head or tread portion thereof, whereupon the rail may be lifted and carried by workmen on either side thereof in much the same manner as the tie 9 is carried in Fig. 4.

30 The teeth 11, when used, and the grips 12 may be bolted or spot-welded to the members 5, or formed integrally therewith, or otherwise rigidly attached thereto. In the construction shown the teeth 8 are integral 35 with the jaws and extend in the planes of the latter. The teeth 11 and the grips 12 are also disposed in the planes of the respective jaws to which they are attached, being secured to the outer sides or faces of the 40 jaws by rivets, 14 and 15 respectively, passing through laterally offset shanks of said teeth and grips. This construction leaves the inner or meeting faces of the tong levers 45 smooth or free from any obstructions, enabling the tongs to be readily opened out to the positions shown in Figs. 3 and 4.

The economy effected by my present invention will be readily appreciated when it is realized that, in the most complete and 50 preferred form of the invention illustrated, a single tool performs three functions which, prior to the invention of the tool disclosed in my pending application, above referred to, were performed by three separate and distinct tools. It will be noted 55 that when the tongs are in either the rail-carrying position (Fig. 3) or the tie-carrying position (Fig. 4) the hand grips 7 extend sufficiently beyond the teeth 8 to prevent any danger of injuring or tearing the

clothes of the workmen through accidental contact with said teeth. It will be further noted that the rail-engaging grips 12 are located so high on the jaws, or so closely adjacent to the pivot thereof, that they do 65 not interfere with the use of the tongs in the tie-placing position (Fig. 2) through interference with the top of the tie.

I claim:

1. Railway tongs of the character described, comprising a pair of tong levers pivoted intermediate their ends, the jaw portions of said levers being provided at their lower ends with inwardly extending teeth adapted to grip a tie, and slightly 75 below their pivot with inwardly extending grips adapted to clamp the web of a rail beneath the head or tread portion of the latter.

2. Railway tongs of the character described, comprising a pair of tong levers pivoted intermediate their ends and each consisting of a straight handle portion on one side of said pivot and a downwardly offset jaw portion on the other side of said pivot 85 terminating in an inwardly turned tooth, and inwardly extending grips on said jaws located slightly below the pivot, said grips being adapted to clamp the web of a rail beneath the head thereof with the handles of 90 the tongs spread to approximately horizontal position.

3. Railway tongs of the character described, comprising a pair of tong levers pivoted intermediate their ends and each 95 consisting of a straight handle portion on one side of said pivot terminating in an outwardly turned hand grip and an outwardly offset jaw portion on the other side of said pivot terminating in an inwardly 100 turned tooth, outwardly extending teeth on said jaws above said inwardly turned teeth, the construction and relation of said parts being such that the lower teeth may be engaged with a tie with the handle portions sufficiently close together to be manipulated by a single operative, and by inverting the implement and swinging said handle portions to the other side of the pivot said outwardly extending teeth may be engaged 105 with the tie with the handle portions spread to approximately horizontal position, and a pair of inwardly projecting grips on said jaw portions closely adjacent to and slightly below the pivot, said grips being adapted to clamp the web of a rail beneath the head thereof with the handle portions spread to approximately horizontal position.

CHARLES H. LUTHMAN.
